J. J. DIVO,
AUTOMATIC SWITCH FOR MAIN AND AUXILIARY CIRCUITS,
APPLICATION FILED DEC. 3, 1918.

Patented Oct. 5, 1920.

WITNESSES:

ATTORNEY

UNITED STATES PATENT OFFICE.

JOHN JACOB DIVO, OF BROOKLYN, NEW YORK.

AUTOMATIC SWITCH FOR MAIN AND AUXILIARY CIRCUITS.

1,354,897.

Specification of Letters Patent.

Patented Oct. 5, 1920.

Application filed December 3, 1918. Serial No. 265,092.

To all whom it may concern:

Be it known that I, JOHN JACOB DIVO, a subject of Turkey, residing at Brooklyn, county of Kings, State of New York, have 5 invented an Improvement in Automatic Switches for Main and Auxiliary Circuits, of which the following is a specification.

This invention has for its object to provide an automatic switch, which may also be operated manually, and which is especially adapted for use wherever there is a main circuit and an auxiliary circuit which is liable to be called into use at any time should a break occur in the main circuit, as 10 for example main and auxiliary dynamo circuits, or main and auxiliary lighting circuits in a factory, dwelling or car, the first use being to automatically switch in an auxiliary dynamo should the main dynamo 15 break down, and the second use, which I have illustrated in the drawing, being to automatically switch in an auxiliary lighting circuit, *i. e.* a battery circuit, should a break occur in the main circuit.

20 With the above and other objects in view, I have devised the novel automatic switch which I will now describe referring to the accompanying drawing forming a part of this specification and using reference characters to indicate the several parts.

25 Figure 1 is a view partly in elevation, partly in section, and partly diagrammatic illustrating the normal use of my novel switch, the main circuit contacts being in the closed circuit position, and the auxiliary circuit contacts being in the open circuit position;

30 Fig. 2 a similar view in which a break has occurred in the main circuit; and the switch has closed the auxiliary circuit; and

35 Fig. 3 is a similar view showing the position of the parts when the switch has been operated manually to open the main circuit, as in shutting off the current in an apartment upon retiring, or in a suite of offices upon closing.

40 10 denotes an insulating body within which is seated an electro-magnet 11, whose core 12 is extended below the coils of the magnet and is provided with opposite notches 13. 14 denotes the main circuit wires, 15 and 16 the main circuit contacts, the latter being a spring contact and normally acting to close the circuit, 17 the aux-

iliary circuit wires, 18 the battery and 19 55 and 20 the auxiliary circuit contacts, the latter being a spring contact and being provided with an enlargement 21 which serves as an armature for the electromagnet. 22 denotes a shaft which has rotary and longitudinal movement in the core of the electro-magnet, is provided with a cross pin 23 which is adapted to engage the notches in the lower end of the core, as in Figs. 1 and 2, or to ride out of the notches and upon 60 the high portions of the end of the core between the notches, as in Fig. 3. The shaft is retained in its normal position, that is with the cross pin in engagement with the notches, by means of a spring 24 which 65 bears against the body and against the finger piece 25 by which the shaft is manually operated to open the main circuit, as in Fig. 3. This is effected through the endwise engagement of the shaft with main circuit 70 contact 16. A collar 26 on the shaft is adapted to engage enlargement 21 on contact 20 to retain the auxiliary circuit open, as in Fig. 3. A break in the main circuit is indicated by 27 in Fig. 2.

75 The operation will be readily understood from the drawing. In Fig. 1 the main circuit is closed and the electro-magnet is energized, which has drawn contact 20, also serving as an armature, into engagement 80 with the core, thus opening the auxiliary circuit and retaining it open so long as the electro-magnet remains energized. In Fig. 2 a break has occurred in the main circuit which has deenergized the electro-magnet 85 and released contact 20 which instantly engages contact 19, thereby closing the auxiliary circuit, and in the case of lighting circuits, as illustrated in the drawing, lighting the lamps of an auxiliary circuit the instant 90 the lamps in the main circuit are extinguished. Fig. 3 illustrates the ordinary, every day use of the switch in opening the main circuit (the auxiliary circuit being already open) and retaining both circuits 95 open when use of the main circuit is not required. A quarter rotation of the shaft will cause the cross pin to pass out of the notches in the end of the core and ride up on the high portions thereof. This will draw the 100 shaft downward, the end of the shaft will force contact 16 out of engagement with contact 15, and collar 26 will engage en-

largement 21 (the armature) of contact 20 and retain said contact out of engagement with contact 19.

Having thus described my invention, I claim:

1. A switch of the character described comprising an electro-magnet, a main circuit which energizes said magnet, contacts in said circuit, an auxiliary circuit, contacts 10 in said circuit one of which serves as an armature, a shaft carried by said switch and adapted to engage a contact in each circuit to open the main circuit and hold both circuits open, and means for producing longitudinal movement of said shaft when rotated.

2. A switch of the character described comprising an electro-magnet, a main circuit which energizes said magnet, contacts in 20 said circuit, an auxiliary circuit, contacts in said circuit one of which serves as an armature, a shaft having endwise engagement with one of the main circuit contacts and having a collar adapted to engage an auxiliary circuit contact, and means for producing longitudinal movement of said shaft when rotated, whereby the main circuit is opened and both circuits retained open.

3. A switch of the character described comprising an electro-magnet, a main circuit which energizes said magnet, contacts in said circuit, an auxiliary circuit, contacts in said circuit one of which serves as an armature, a magnet core having opposite 35 slots and high portions between the slots, and a shaft which is adapted to engage a contact in each circuit, said shaft adapted to have rotary and longitudinal movement in said core and being provided with a cross

pin which is adapted to engage said slots 40 and high portions.

4. A switch of the character described comprising an insulating body, an electro-magnet seated therein and having a core provided at one end with opposite notches 45 and high portions, a main circuit which energizes the magnet, contacts in said circuit, an auxiliary circuit, contacts in said circuit one of which serves as an armature, a shaft in said core having endwise engagement 50 with a main circuit contact and having a collar adapted to engage an auxiliary circuit contact, and a cross pin adapted to engage the notches and high portions of the core, and a spring acting to retain the shaft 55 in its normal position.

5. A switch of the character described comprising an electro-magnet, a plurality of contacts, a magnet core having opposite slots and high portions between the slots, 60 and a shaft which is adapted to engage said contacts, said shaft adapted to have rotary and longitudinal movement in said core and being provided with a cross pin which is 65 adapted to engage said slots and high portions.

6. A switch of the character described, comprising an electro-magnet, contacts at opposite ends of said magnet; a magnet core having opposite slots and high portions between the slots, and a shaft which is adapted to engage said contacts, said shaft adapted to have rotary and longitudinal movement in said core and being provided with 70 a cross pin which is adapted to engage said 75 slots and high portions.

In testimony whereof I affix my signature.
JOHN JACOB DIVO.
